CLAIM

The ornamental design for a bollard luminaire, as shown and described.

DESCRIPTION

FIG. 1 is a perspective view of a bollard luminaire, showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a perspective view of another new ornamental design for a bollard luminaire;

FIG. 9 is a front elevation view of the luminaire of FIG. 8;

FIG. 10 is a rear elevation view of the luminaire of FIG. 8;

FIG. 11 is a right-side elevation view of the luminaire of FIG. 8;

FIG. 12 is a left-side elevation view of the luminaire of FIG. 8;

FIG. 13 is a top plan view of the luminaire of FIG. 8; and,

FIG. 14 is a bottom plan view of the luminaire of FIG. 8.

The broken lines shown represent unclaimed subject matter and form no part of the claimed design.
